DOOR HANDLE ASSEMBLY

John H. Roethel, Detroit, Mich., assignor to
 Roethel Engineering Corporation, Detroit,
 Mich., a corporation of Michigan

Application May 15, 1950, Serial No. 162,057

3 Claims. (Cl. 292—336.3)

1

This invention relates to door handle assemblies, especially for automobile doors, and refers more particularly to a type of outside door handle having an integral housing portion adapted to receive therein a push button means for actuating a latch mechanism to permit the door to be opened.

In the present invention the handle is formed so that the hand grip portion extends above and beyond the portion forming the housing in which the push button means is mounted so as to provide a shield overlying the push button. This shield portion of the handle thus protects the push button against damage in the event the door is swung into an obstruction or is struck by an object such as another swinging door, as frequently occurs when vehicles are parked close to each other in a parking area. The shield portion of the handle also acts as a deflector preventing the accumulation of water and snow about the push button and thus reducing the possibility of the push button freezing within the housing during cold weather.

It is an object of the invention to provide a door handle of the foregoing general description which has an attractive appearance, is relatively inexpensive to manufacture, is of sturdy construction to withstand any stresses placed thereon, is easily installed on the vehicle door, and provides a means of mounting the push button so that it may be efficiently and effectively pushed inwardly to actuate the latch mechanism.

It is a further object of the invention to provide a handle assembly having a push button which may be pushed inwardly by thumb pressure with a minimum of strain on the thumb. When the hand is extended palm down to grasp the hand grip portion of the handle assembly, the thumb in its most relaxed position will lie below the plane of the palm. Accordingly, the push button is located below the longitudinal axis of the hand grip portion and thus is in a position to be engaged by the thumb without contortive movement of the latter.

This application is a continuation in part of my copending application 77,519, filed February 21, 1949.

Other details and objects of the particular embodiment of the invention herein illustrated will appear in the following description, reference being had to the accompanying drawings forming a part of the specification wherein like reference numerals designate corresponding parts in the several views.

2

Fig. 1 is a fragmentary side elevation of a portion of an automobile body provided with swinging doors upon which door handles made in accordance with the present invention are installed.

Fig. 2 is an enlarged fragmentary vertical section taken substantially through lines 2—2 of Fig. 1 looking in the direction of the arrows.

Fig. 3 is a fragmentary vertical section taken substantially through lines 3—3 of Fig. 2 looking in the direction of the arrows.

Before explaining in detail the present invention it is to be understood that the invention is not limited in its application to the details of construction and arrangement of parts illustrated in the accompanying drawings, since the invention is capable of other embodiments, and of being practiced or carried out in various ways. Also it is to be understood that the phraseology or terminology employed therein is for the purpose of description and not of limitation.

In the drawings there is illustrated by way of example, one embodiment of the present invention as applied to the door of an automobile body. As illustrated in Fig. 1 the automobile body, generally designated at A, is provided with a front door B which is hinged at its front edge so as to swing against a door post or body pillar in accordance with conventional practice. The door comprises an outer metal door panel 10 which terminates as is customary in a transverse jamb edge or portion 11 facing the fixed jamb face or edge of the door frame post or body pillar.

The illustrated handle assembly, generally designated 12, is shown mounted on the outer side of the door panel in operative relationship to a latch device, generally designated 13, mounted within the door frame structure. It will be understood, however, that the invention is not limited to the particular latch device herein employed by way of example.

The illustrated latch device 13 comprises a case plate 14 provided with screw bosses 14a by means of which the case plate is secured to the inner side of the jamb portion 11 of the door. The case plate terminates at its inner edge in a flange 15 facing the inner door panel (not shown). The latch device is preferably provided with a rotatable toothed latch or bolt 16 positioned at the outer face of the case plate 14, this latch or bolt having an integral projecting shaft or shank 17 extending through an aperture in the case plate which is formed with 55 a bearing for the bolt shaft. The inner end of

the shank 17 of the bolt is flattened and extended through a correspondingly shaped aperture in a rotatable toothed detent engaging member or ratchet member 18 and is riveted thereto.

The rotatable latch bolt 16, as shown in dotted outline in Fig. 2, is formed with a number of radially projecting tooth-like projections 16a, preferably six, which are spaced equally around the periphery of the bolt so as to provide in effect a gear type latch or bolt. The ratchet member 18 is also formed around its periphery with a number of tooth-like abutments or projections 18a which correspond in number to the tooth-like projections 16a of the bolt. Pivotally mounted on a shoulder rivet 19 secured to the case plate 14 is a swinging detent, pawl, or dog which has a downwardly extending detent arm 20 cooperable with the teeth or projections 18a of the ratchet member 18. The detent arm 20 is engageable with any one of the teeth 18a in the manner shown in Fig. 2 to hold the ratchet member and hence the bolt 16 in a locking position against rotation in a clockwise direction as viewed in Fig. 2. Extending from the outer part of the detent arm 20 in an outward and downward direction is a second arm 21, this arm lying substantially in the plane of the ratchet member 18 and spaced outwardly therefrom.

Associated with the detent is a vertically extending detent actuating or release lever 22 which is pivoted intermediate its ends upon a shoulder rivet or stud 23 secured to the case plate. This lever has a lever arm 24 extending downwardly below the pivot 23 and terminating in a hook-like projection 24a which overlies the detent arm 21. The inner end of the hook-like projection 24a is embossed to form a curved lug 24b engaging the inner edge 21a of the detent arm 21. By virtue of this construction the lever arm 24 and detent arm 20 are interconnected by means of the lug or projection 24b on the hook-like portion 24a engaging beneath the extended portion of the detent arm 20. The detent release lever 22 also has an upwardly extending lever arm 25 formed with an inwardly extending projecting portion 26. The upper end of the lever arm is enlarged and formed with a widened flange 25a. The detent release lever is also provided with an inwardly extending arm 27.

The detent arm 20 is yieldingly urged toward the ratchet plate 28 and the release lever 22 is similarly urged toward its normal position shown in Fig. 2 by means of a single coiled spring 28 anchored at its inner end to a retainer 29 lanced out of the case plate. This spring has a downwardly extending arm 28a engageable with the upper edge of the detent arm 20 so as to yieldingly hold the arm in latching engagement with a tooth 18a of the ratchet member 18. Due to the interlocking connection between the hook-portion 24a of the release lever 22 and the extension 21 of the detent arm 20, the spring 28 will also function to urge the lever arm 24 inwardly and the lever arm 25 outwardly so as to maintain them in the normal non-operated position shown in Fig. 2. Outward movement of the release lever under the influence of the spring is limited by a stop 30 which is in the form of a lug struck out from the edge of the case plate and positioned for engagement by the outer edge of the lever arm 25, as shown in Fig. 2. A light anti-rattle spring 31 may be provided to hold the lever arm 25 against the stop 30 when the detent arm 20 is swung upwardly relative to the lever arm 25. The coiled

spring 31 is suitably selected as to strength and has one arm connected to the lever arm 25 and the opposite end connected to the case plate 14.

A resilient bumper 32 is fastened to the case plate 14 in position to be engaged by the end portion 21b of the detent arm 21 to minimize any noise which might occur as the pawl 30 is urged into abutting relation with the teeth 18a by the spring 28.

The release lever 22 of the latch device 13 may be swung so that its arm 24 will lift the detent arm 20 out of engagement with the ratchet 18 either by an operator accessible from the outside of the vehicle or by one accessible from the inside of the vehicle. In Fig. 2, a fragmentary portion 33 of a bell crank lever arm is shown overlying the release lever arm 21. Downward movement of the arm 33 upon actuation of a remote control mechanism handle on the inside of the door which is connected to the bell crank lever 33 will cause the arm 21 of the release lever to be swung downwardly. The resulting pivotal movement of the release lever 22 will cause the arm 24 to lift the detent arm 20 out of engagement with the ratchet 18 and will thus permit the door to be unlatched. A further detailed description of the remote control mechanism is not deemed necessary herein as the construction and arrangement of this mechanism forms no part of the present invention.

The latch device 13 has incorporated therein a member for blocking swinging movement of the release lever arm 25 toward the flange 15. The blocking member comprises a slide 34, a fragmentary portion of which is shown in Fig. 2. The slide 34 may be shifted so that an upwardly extending channel shaped projection 35 thereon will be interposed between the projection 26 on the release lever 22 and the flange 15, thus blocking swinging movement of the release lever arm 25 toward the flange. A further detailed description of the slide 34 and the mechanism for shifting the projection 35 thereon into and out of blocking relation to the projection 26 on the release lever arm 25 is also not deemed necessary herein as the construction and arrangement of the shifting mechanism does not pertain to the present invention.

In the present embodiment of the invention a push or plunger type outside operator is provided for swinging the detent release lever 22 so as to raise the detent arm 20 out of engagement with the teeth 18a of the ratchet member to permit the door to be opened. A handle assembly, hereinbefore generally designated 12, is rigidly secured to the outside door panel 20. The handle assembly 12 comprises a suitably contoured hand grip portion 36 formed integrally at one end with a housing portion 37 constructed to form a mounting for a push button 38. This push button 38, as best seen in Fig. 3, projects through an aperture 39 in the housing portion 37 and is slidable therein within a cylindrical bore 40. A preferred method of preventing withdrawal of the push button 38 from the bore is the provision of an integral flange 38a formed on the push button, the flange having a diameter less than the diameter of the bore 40 but greater than the diameter of the aperture 39.

The push button 38 has an integral reduced cylindrical extension or stem 41 which carries on its end an enlarged knob or button 42. When the handle assembly is mounted on the body panel the stem 41 projects through an aperture

43 in the body panel and the button 42 abuts the flange 25a of the lever arm 25. Mounted within the bore 40 is a retainer piece 43 having a central aperture through which the stem 41 extends freely. Interposed between the retainer piece 43 and the flange 38a of the push button is a coiled return spring 44 which serves the purpose of urging the push button outwardly to its normal position, as shown in Figs. 2 and 3. The retainer piece 45 is held within the bore 40 by a snap ring 45 seated in a groove 46 in the wall of the bore.

The forward end of the hand grip portion 36, as viewed in Fig. 1, is provided with a hook portion 47. In mounting the handle on the body panel the hook 47 is inserted through an aperture 48 in the body panel and engaged with the panel edge as shown in Fig. 3.

The end of the hand grip portion 36 adjacent the push button housing is provided with a projecting boss 49 having a tapped hole 50 therein. The boss 49 is inserted into an aperture in the body panel and the hole 50 is aligned with an aperture 51 in the jamb 11 of the door B. A bolt 52 is then inserted through the aperture 51 and threaded into the hole 50, thus fastening the handle to the body panel.

As illustrated in Figs. 1 to 3 inclusive, the hand grip portion 36 of the handle assembly 12 is formed integrally with an outwardly projecting portion 36a which extends above and beyond the push button 38 so as to form a shield overlying the push button. The provision of the shield eliminates several disadvantages that would result if the push button projected outwardly from the body panel further than the adjacent portion of the handle. For example, when the release lever 25 is blocked against movement toward the flange 15 the push button 38 is also blocked against inward movement since the knob or button 42 of the push button stem 41 abuts the flange 25a of the release lever. Thus, any object striking the push button a sufficiently hard blow could cause the push button stem 41 or the lever flange 25a to become bent, or would otherwise cause damage to the mechanism. In crowded parking areas it is a frequent occurrence for vehicle doors to be swung into the body panel of an adjacent vehicle with sufficient force to damage the panel. The provision of the shield protects the push button against being struck by such a swinging door.

The shield portion of the handle also acts as a deflector preventing the accumulation of water and snow about the push button and thus reduces the possibility of the push button freezing within the housing during cold weather.

The location of the push button below the longitudinal axis of the hand grip portion of the handle assembly is advantageous in that it minimizes strain on the thumb when thumb pressure is exerted to push the button inwardly. When the hand is extended palm down to grasp the hand grip, the thumb in its normal position will extend below the plane of the palm. Thus, a push button positioned below the longitudinal axis of the hand grip portion will lie substantially in the path of straight inward movement of the thumb without requiring the thumb to be subjected to twisting movement.

Preferably, the hand grip portion 36 and the

integral shield portion 36a has a cross sectional contour as shown in Fig. 2. As shown, the upper surface 36b slopes downwardly and the under surface 36c slopes upwardly, thus giving the handles a diminishing cross sectional thickness from the body panel outwardly. The downwardly sloping upper surface 36b aids in providing run-off of water falling on the handle. The upwardly sloping lower surface 36c provides clearance for the thumb as it is moved inwardly to depress the push button 38.

I claim:

1. A door handle assembly for a vehicle body comprising a hand grip member adapted to be secured to the body at opposite ends thereof, said member terminating at one end in a butt portion and an underlying housing portion integral therewith and depending therefrom, the outer face of said housing portion lying a substantial distance inwardly of the outer edge of said butt portion, a slideable push button mounted in said housing portion and normally projecting outwardly of the outer face thereof and below said butt portion, the latter projecting outwardly of and beyond the outer end of the push button to form a protective shield overlying the push button.

2. A latch actuating device comprising a handle adapted to be mounted on a vehicle outer body panel and having a hand grip portion and a housing portion integral therewith located at one end of the handle at a level below said hand grip portion thereof, said housing portion being disposed for mounting on the outer face of said body panel, a slideable push button mounted in said housing portion and having a member adapted to project beyond the plane of the body panel and abut a movable member of a latch device, and an integral shield portion on the end of said hand grip portion projecting outwardly above said push button a distance to overlie and substantially cover the latter.

3. A door handle structure comprising a handle member having a hand grip portion and adapted to be secured to the outer panel of a door, said member terminating at one end in a butt having an integral push button mounting portion located at a level below said hand grip portion and constructed for mounting on the outside of said door panel, a slideable push button mounted in said mounting portion for actuating a movable part of a latch device and normally projecting outwardly of the outer face of said mounting portion, said handle butt having an integral shield portion disposed at a level above the push button and its said mounting portion and projecting outwardly to overlie and cover a substantial portion of said push button.
